PARTITION BASE CLIP

William G. Baum, Milwaukee, Wis., assignor to
 Inland Steel Products Company, Milwaukee,
 Wis., a corporation of Delaware

Application February 9, 1948, Serial No. 7,169

5 Claims. (Cl. 72—46)

1

This invention relates to a partition clip for holding metal base and studs of solid wall partitions in buildings.

The principal object of the invention is to reduce the labor cost for installation of partitions.

Another object of the invention is to provide for the more rapid installation of clips, base members and studs for solid wall partitions.

Another object is to provide a clip upon which the base members may be positioned rapidly and with less effort.

Another object is to provide the required tolerances in levelness of the floor so that the base can be secured upon a plurality of spaced clips disposed in a row on the floor without requiring substantial individual manual adjustment of any of the clips to compensate for normal unevenness of the floor.

Another object is to provide for the automatic adjustment of the clip to the position of the base upon hanging of the latter thereon.

Another object is to provide a simple manual adjustment for the height of the clip without requiring shimming and the like.

Another object is to provide a lower clip with improved means for holding a stud in position.

Another object is to prevent the stud from coming free of the upper runner after insertion and positioning of the stud by substantially reducing the vertical drop of the stud in inserting the same in the lower clip.

Another object is to simplify the construction of the clip and to reduce the number of operations necessary in forming the same.

Another object is to prevent misalignment of clips with each other.

The invention is illustrated in the accompanying drawing in which:

Figure 1 is a perspective view of a solid wall partition with parts broken away and sectioned;

Fig. 2 is a horizontal section taken through a stud and showing a clip and the base in plan view;

Fig. 3 is a transverse vertical section taken on line 3—3 of Fig. 2 and showing the manner of holding the base sections;

Fig. 4 is a transverse vertical section taken on the same line as Fig. 3 and looking towards the opposite direction to show the support for the stud;

Fig. 5 is a longitudinal vertical section taken on line 5—5 of Fig. 2;

Fig. 6 is a view of the clip in side elevation prior to positioning the base and stud on the clip and showing the adjustability in height for the 55 clip;

2

Fig. 7 is a detail perspective view showing the clip and a base section about to be applied thereto;

Fig. 8 is a detail view showing the ceiling runner and the manner of inserting the stud therein; and

Fig. 9 is a detail sectional view showing another form of stud support.

The clip is used in the construction of solid plaster walls 1 wherein metal channel studs 2 are employed and metal lath 3 is secured to the studs on one side thereof for receiving the plaster 4 on both sides of the studs.

Each stud 2 is held in place vertically by a lower clip 5 and an upper runner 6 which are formed from flat strips of sheet metal bent along predetermined lines and cut as hereinafter described.

The lower clip 5 has a base foot 7 which is secured to the floor 8 by a suitable nail 9 or other means. The body 10 of the clip is bent upwardly from the support 7 and has an opening therethrough provided by the forming of a ledge flange 11 bent therefrom along one edge of the opening for supporting the stud 2 at a substantial height above the floor.

The upper end 12 of clip 5 is bent horizontally in the general direction of ledge 11 opposite to the direction of support 7, and has a rectangular opening 13 therein directly above ledge 11 for receiving the lower end of stud 2 and holding the stud against lateral displacement when in position.

The outer free end of the horizontal section 12 of clip 5 is bent upwardly and is provided with an angular upwardly extending ear 14 at each side of the clip.

A base section 15 is hung on each ear 14 of the clip to provide spaced base members flush with the plaster of the partition. Each base section 15 is formed from a flat strip of metal with the longitudinal edges thereof bent to one side on a reverse angle to provide an upper flange 16 and a lower flange 17 forming a partially closed channel for securing the same to a plurality of clips.

The upper flange 16 is hung on the corresponding ears 14 of clips 5, which ears are of wedge shape to enter behind the flange 16 and secure the base section against lateral displacement at its upper edge.

The lower flange 17 snaps beneath a finger 18 extending from body 10 at an angle downward from the horizontal at a level which effects entrance of the free end of the finger behind the flange to thereby secure the base section against lateral displacement at its lower edge.

3

The finger 18 may extend in either longitudinal direction from body 10, but it is preferable to have it extend beneath section 12 since where it extends in the direction of support 7 it may interfere with the application of nail 9 to the clip.

In construction, the outer free ends of fingers 18 will be spaced from the corresponding tops of ears 14 at a distance slightly greater than the space between the corresponding edges of flanges 16 and 17, so that when the base sections 15 are sprung in place on opposite sides of the clip, the sections will be held securely in position.

The end of each finger 18 is formed with an angular edge to serve as a cam for spring action in snapping the base 15 in place.

Each base section 15 is ordinarily positioned with its lower edge on the floor or closely adjacent thereto. Where there is any unevenness of the floor the clips 5 may be adjusted to vary the height of ears 14 and fingers 18 by merely bending body 10 in the right direction relative to support 7, as shown in Fig. 6.

The runner 6 securing the upper ends of the studs is constructed of sheet metal having a horizontal flange 19 extending along the upper edge thereof and with holes for nailing the runner to the ceiling 20. The flange 21 extends horizontally from the lower edge of the runner oppositely of upper flange 19 and is provided with a series of rectangular openings 22 to receive the upper ends of studs 2.

The installation of a partition may be substantially as follows: after the plane of the partition is located along a line on the floor and a similar line on the ceiling, the clips 5 are nailed in place in a row along the line and spaced apart corresponding to the desired spacing for the studs 2, and the runner 6 is secured to the ceiling along the corresponding line. The base sections 15 are then applied to the opposite sides of the lower clips 5. Then the upper end of a stud 2 is inserted upwardly through the opening 22 of runner 6 until the lower end of the stud clears the top of the corresponding clip 5. The lower end of stud 2 is then dropped vertically into opening 13 until it rests upon ledge 11. The distance of vertical drop for the stud 2 in entering opening 13 is substantially less than the distance which the upper end of the stud moves in insertion thereof upwardly through opening 22, so that when the stud comes to rest on ledge 11 there will be no danger of the upper end of the stud coming free from runner 6.

The ledge 11 may be variously constructed so long as it is disposed at a height sufficient for the stud and so long as it serves to prevent accidental dropping of the stud past the ledge.

In Figs. 3 and 4 the ledge 11 is bent from the body 10 at the upper edge of opening in the body and disposed horizontally. The ledge 11 has a length along body 10 substantially greater than the width of the channel stud. The ledge 11 extends outwardly from body 10 a distance nearly equal to the width of opening 13.

In Fig. 9 the ledge 11 is shown as bent at an acute angle from body 10 at the lower edge of the opening in the body, and has its upper edge disposed at the desired level for supporting the stud 2. In this construction the upper edge of ledge 11 should be spaced a distance from body 10 slightly less than the minimum depth of the channel stud 2. Likewise the upper edge of ledge 11 should be spaced from the vertical plane of the outer edge of opening 13 a distance which is less than the depth of the stud 2.

4

After placing of the several studs in the corresponding clips, the metal lath 3 is applied to the studs and then plaster 4 is applied from opposite sides to complete the partition.

The invention avoids the necessity of shimming clips and provides a clip that greatly facilitates the construction of the partition.

The corner edge 23 between the body section 10 and the upper horizontal section 12 should be disposed at a level lower than the level for the upper flange 16 of each base section 15 so that there is no interference between the clip and base sections when the latter are applied over the ears 14. Likewise, the level of the bend 24 between fingers 18 and body 10 should be disposed above the level for the lower flange 17 of the corresponding base section 15 so that there is no interference between the clip and base when the latter is applied.

The width of the clip should correspond to the spacing of the base sections and should depend upon the thickness of wall desired.

The clip is constructed from a flat strip of sheet metal having a width corresponding to that of the body and upper sections and which corresponds to the spacing of the vertical webs of the opposite base sections. The strip is slit to provide the fingers 18 and supporting foot 7 and the ledge 11 and opening 13.

The first operation is a blanking one in which the strip is slit to provide the fingers 18 and supporting foot 7, the ledge 11, opening 13 and the ears 14. In this operation several of the bending movements may be either started or completed, and the next operation completes all of the remaining bending movements and severs the foot end of the blank from the strip.

Various embodiments of the invention may be employed within the scope of the accompanying claims.

I claim:

1. A solid wall partition clip formed of sheet metal and adapted to be secured to a floor for holding a stud and metal base sections, each base section having reverse inwardly directed flanges extending along their upper and lower edges, said clip comprising a vertical body section having a support at its lower edge for securing the same to the floor, a pair of base locking members on each side of said body section and extending laterally from the plane of the body section with the outer ends of the locking members of each pair spaced vertically apart to engage behind the upper and lower flanges on a base section and with a resilient locking effect, the upper locking member of each pair being formed on a single common upper generally horizontal section bent from the upper edge of said body section to provide for a substantially common level for the base sections on opposite sides of the clip, said upper horizontal section having an opening therein for receiving the lower end of a stud and preventing lateral displacement thereof, and a ledge struck from said body section and disposed beneath said opening to support the stud at a height substantially above the floor.

2. A solid wall partition clip formed of sheet metal and adapted to be secured to a floor for holding flanged metal base sections and a stud, said clip comprising a vertical body section bent upwardly from a horizontal supporting section along a transverse line, a substantially horizontal upper section bent laterally from the upper edge of said body section in a direction opposite to the direction of said supporting section, a base

supporting ear at each outer corner of said upper horizontal section disposed to receive and lock behind the upper flange of a base section, and a resilient locking finger bent generally horizontal from the body section and having a locking surface adapted to engage behind the lower flange of a base section for locking the latter in place, said finger and said horizontal upper section cooperating to resiliently engage the corresponding flanges of the base section to maintain the locking action referred to and being yieldable toward each other to provide for assembly and disassembly of the base sections with the clip.

3. A solid wall partition clip formed of sheet metal and adapted to be secured to a floor for holding flanged metal base sections and a stud, said clip comprising a vertical body section bent upwardly from a horizontal supporting section along a transverse line, a substantially horizontal upper section bent laterally from the upper edge of said body section in a direction opposite to the direction of said supporting section, a base supporting ear at each outer corner of said upper horizontal section disposed to receive and lock behind the upper flange of a base section, a resilient locking finger bent generally horizontal from the body section and having a locking surface adapted to engage behind the lower flange of a base section for locking the latter in place, said finger and said horizontal upper section cooperating to resiliently engage the corresponding flanges of the base section to maintain the locking action referred to and being yieldable toward each other to provide for assembly and disassembly of the base sections with the clip, said horizontal upper section having an opening therein disposed to receive the lower end of a stud, and a ledge struck from said body section and disposed beneath said opening to support the stud.

4. A solid wall partition clip formed of sheet metal and adapted to be secured to a floor for holding metal base sections having reverse inwardly directed flanges extending along their upper and lower edges, said clip comprising a vertical body section having a support at its lower edge for securing the same to the floor, and a pair of base locking members on each side of said body section and extending laterally from the plane of the body section with the outer ends of the locking members of each pair spaced

vertically apart to engage behind the upper and lower flanges on a base section and with a resilient locking effect, each lower locking member constituting a finger bent generally horizontal from the body section and having a locking surface adapted to engage behind the lower flange of the corresponding base section for locking the latter in place.

5. A solid wall partition clip formed of sheet metal and adapted to be secured to a floor for holding metal base sections having reverse inwardly directed flanges extending along their upper and lower edges, said clip comprising a vertical body section having a support at its lower edge for securing the same to the floor, and a pair of base locking members on each side of said body section and extending laterally from the plane of the body section with the outer ends of the locking members of each pair spaced vertically apart to engage behind the upper and lower flanges on a base section and with a resilient locking effect, the upper locking member of each pair being formed on a single common upper generally horizontal section bent from the upper edge of said body section to provide for a substantially common level for the base sections on opposite sides of the clip, each lower locking member constituting a finger bent generally horizontal from the body section and having a locking surface adapted to engage behind the lower flange of the corresponding base section for locking the latter in place, said horizontal upper section and said fingers cooperating to resiliently engage the corresponding flanges of the base sections to maintain the locking action referred to and being yieldable toward each other to provide for assembly and disassembly of the base sections with the clip.
